UNITED STATES PATENT OFFICE.

GEORGE R. WADSWORTH, OF CLEVELAND, OHIO, ASSIGNOR TO THE PEERLESS MOTOR CAR COMPANY, OF CLEVELAND, OHIO, A CORPORATION OF OHIO.

STARTER FOR INTERNAL-COMBUSTION ENGINES.

1,207,821.

Specification of Letters Patent. Patented Dec. 12, 1916.

Application filed November 8, 1911. Serial No. 659,100.

To all whom it may concern:

Be it known that I, GEORGE R. WADSWORTH, a citizen of the United States, residing at Cleveland, in the county of Cuyahoga and State of Ohio, have invented a certain new and useful Improvement in Starters for Internal-Combustion Engines, of which the following is a full, clear, and exact description.

10 This invention relates to starters for internal combustion engines, especially engines employed in motor vehicles.

It has been proposed to start an internal combustion engine of a motor vehicle by 15 means of an electric motor comprising a fixed field member and an armature which is mounted directly upon the crank shaft or an extension thereof, and has its axis of rotation coincident with the axis of the crank 20 shaft. In a starting device of this kind wherein the power of the motor is applied directly to the crank shaft without any intermediate power-multiplying transmission agency, it is essential that the motor have 25 a very large starting torque, and by reason of the great load on the motor, a heavy starting current is required by the motor. This is very objectionable for automobile service, for the reason that during the operation 30 of the starting motor, there is a very heavy drag on the storage battery, which is very detrimental to its life and efficiency.

The present invention relates to starters of this particular type, and has for its main 35 object to improve the efficiency of the starter, and to render it more suitable and effective for the purpose intended.

More specifically considered, my invention aims to provide an improved method of 40 utilizing and applying to the crank shaft of the engine the power or turning effort of the motor, so that a motor of low starting torque and requiring a low starting current can very effectively turn over or start the 45 engine.

Furthermore, my invention relates to an apparatus by which the method can be carried out in a very satisfactory manner.

With my improved method, instead of 50 starting the motor retarded by the load of the engine, and thus starting the engine by the developed starting torque of the motor, I disconnect the rotary element of the motor from the crank shaft by a suitable clutch

which is opened, just prior to the connecting 55 of the motor to the battery, and allow the motor to speed up without load. The rotating element of the motor is made quite heavy, so that it may serve both as a motor element for starting purposes, and as a fly 60 wheel for normal engine operation. Consequently, by reason of its momentum, when it is rotating at a high speed, it has stored up ample energy for starting the engine, but during the interval that it is starting 65 and getting up to full speed, it is drawing only a small current from the battery. To then start the engine, I have simply to clutch the rapidly rotating fly wheel and motor element to the crank shaft of the engine. In 70 carrying out this method, I employ two clutches, one for connecting the fly wheel and motor element to the crank shaft, and the other for connecting the same to the transmission shaft. The former clutch is 75 opened only for starting purposes, and during normal engine operation is thrown in, but the clutch which connects the fly wheel and motor element to the transmission shaft may be thrown in or out at will, and serves 80 the purpose of the clutch ordinarily employed in a motor vehicle. I employ in addition to the above parts, suitable mechanism which may be operated by the hand or foot of the operator for effecting the starting 85 of the engine, and this mechanism preferably serves to throw out the clutch between the crank shaft and the fly wheel and motor element, when it is desired to start the engine, and to simultaneously lower 90 the brushes onto the commutator, and connect the motor to the source of current.

As far as certain features of my invention are concerned, it is immaterial whether or 95 not the length of time that the motor is rotating without load, and consequently the length of time that the clutch is thrown out, is under the control of the operator, but I consider it within the scope of my invention to so arrange and control the mechanism 100 that when the motor reaches a predetermined speed, the clutch is automatically thrown in so as to connect the fly wheel and motor element to the crank shaft, to cause the engine to be started.

My invention may be further briefly summarized as consisting in certain novel steps 105 of an improved method of starting the en-

gine and in certain novel combinations and arrangements of parts of the starting mechanism which will be described in the specification and set forth in the appended claims.

5 In the drawings, Figure 1 is a vertical sectional view showing a portion of my improved starter, and a portion of the engine with which the starter is employed; Fig. 2 shows a side view of a portion of a motor 10 vehicle with my invention applied thereto, certain parts being broken away; Fig. 3 is a sectional view substantially along the line 3—3 of Fig. 1, showing particularly the clutch between the engine and the motor 15 armature; Fig. 4 is a view looking toward the rear side of the motor and showing particularly part of the brush and switch shifting mechanism; Fig. 5 is an enlarged sectional view showing the magnetic governor for the motor; Fig. 6 is a diagrammatic 20 view of the electrical connections.

In the drawings, 10 represents the body of a motor vehicle, and 11 the internal combustion engine, both of which may be of the 25 usual or any suitable construction.

Just at the rear of the engine, and surrounding the rearwardly extending portion of the crank shaft, I provide the starting motor 12, which includes a stationary field 30 element 13, and a rotary armature 14 which is designed to rotate freely about the axis of the crank shaft just preceding the starting of the engine and at all other times is designed to be clutched to the crank shaft. 35 In fact, during normal engine operation, the armature constitutes one of the driving elements between the crank shaft and the transmission shaft, and serves also as the engine fly wheel, the rim of the armature 40 and fly wheel being made heavy in order that it may have considerable momentum when in rotation.

Between the crank case of the engine and the armature, I provide a clutch 15 which 45 is designed to connect and disconnect the engine crank shaft and the motor armature and fly wheel element. It will be understood that at all times, except during the starting of the engine, this clutch is thrown 50 in so that the crank shaft and armature rotate in unison. The clutch 15 includes an overhanging portion of the rim of the armature, and a plurality of arc-shaped shoes 55 16 which are designed to be held in frictional engagement with the inner surface of the rim or to be moved inwardly away from the same. These clutch shoes are guided for inward and outward movement by a radially projecting flange plate 17, and 60 are designed to be shifted and locked in engagement with the outer member of the clutch by a series of links 18 connected to an annular member 19 mounted for sliding movement on a cylindrical member 20, which 65 together with the clutch shoe guiding means

17 is secured to a flange of the crank shaft. The clutch is adapted to be thrown in by a spring 21 and is thrown out against the tension of the spring by the ordinary clutch ring and rock arms which are secured to 70 a rock shaft 22, which is designed to be shifted by mechanism to be referred to presently. While I have shown and described one particular form of clutch, any other suitable form may be employed. 75

The armature and fly wheel element also has a rearwardly projecting cylindrical extension 23, which forms one of the elements of a clutch 24, designed to connect and disconnect the motor armature or the crank 80 shaft of the engine and the transmission shaft, a portion of which is shown at 25. This clutch 24 is here shown as a cone clutch, but it is obvious that a clutch of any other suitable form may be employed, it being 85 understood that this clutch is to be thrown in or out at the will of the operator to connect or disconnect the engine and transmission shaft in the usual manner. The male member of this clutch 24 consists of 90 a cone 26 which is designed to be thrown into engagement with the outer clutch member by a spring 27, and to be thrown out by clutch shifting mechanism, of any suitable type. The rearwardly extending cylindrical flange 23 of the motor armature and fly wheel constitutes a support for the segments 28 of the commutator of the armature, which segments are connected to the 95 armature coils in the usual manner. 100

As before stated, it is one of the features of the present invention to start the engine, not by the developed starting torque of the motor which must in such case be high, in view of the absence of power multiplying transmission between the motor and engine, but by allowing the motor to start and speed up, disconnected from the engine, and hence without load, and thence by utilizing kinetic energy stored up in the rotating element by reason of its weight and momentum for starting purposes by throwing in the clutch between this rotating element and the engine crank shaft. 110

Another feature of my invention resides 115 in the manner in which the motor controlling apparatus, including the switch and the commutator brushes are actuated simultaneously with the actuation of the clutch between the motor element and the engine. 120 Inasmuch as the motor does not function as a motor except when the engine is being started, or just prior to the actual starting of the engine, I have provided a unitary mechanism for shifting the clutch and for 125 simultaneously actuating the switch which connects the motor to the source of current and for moving into engagement with the commutator segments or out of engagement therewith, the commutator brushes. These 130

results could be carried out by several specifically different forms of actuating mechanisms, but the mechanism here shown answers the requirements very effectively. In 5 this case, I employ for connecting the motor to the source of current, (which in a motor vehicle will consist of a storage battery), a switch 29, of the knife blade type, including stationary springs 30, and switch 10 blade 31. Acting in conjunction with the commutator segments 28 are a pair of brushes 32. As the brushes convey current to and from the commutator only during the time that the engine is being started, or 15 while the armature is getting up to speed, I prefer that, except during the time that they are actually employed for conveying current, they be withdrawn from the commutator by a suitable mechanism which acts in 20 conjunction with the switch 29 and clutch 15. It will be noted that the movable switch member 31 is mounted on the rock shaft 33, and that this rock shaft has an arm 34 which is arranged to move the brush into engagement 25 with the segments of the commutator, or away from the same as the rock shaft is shifted. In other words, when the rock shaft is actuated to close the switch, the arm 34 moves the brush into engagement 30 with the commutator and vice versa. It will be understood that the other brush may be actuated by a continuation 33^a of the rock shaft 33, and an arm similar to the arm 34, as indicated in Fig. 4, or by corresponding 35 parts which are actuated with or by the rock shaft 33. A part of the motor housing which projects inwardly over the commutator, constitutes a support for guides for the brushes, bearings for the rock shaft 33, and 40 a support for the switch springs 30, as shown in Figs. 1, 2 and 4.

The switch, the commutator brushes, and clutch 15 may be actuated at the will of the operator or driver of the car either by a 45 hand, lever or foot pedal, but I prefer the latter arrangement. In the present case, I employ a lever 35 which projects up through the bottom of the car so that it is within reach of the foot of the driver. The forward end of this lever is secured to a rock shaft 36, which is beneath the footboard. This rock shaft is connected by means of a rigid arm 37 and link 38 to an arm 39 connected to the rock shaft 22, for shifting the 55 clutch 15. The rock shaft 36 is also connected by a rigid arm 40 and a link 41 to an arm 42 rigid with the rock shaft 33 for shifting the switch and brushes. It will be seen therefore that when the foot pedal is 60 depressed, the clutch 15 is thrown out, the brushes are moved into engagement with the commutator, and the switch is closed so as to connect the motor to the source of current so that the motor is free to start and 65 speed up without load.

The mechanism can be so arranged that the operator may control the time that the motor is allowed to run freely, and may allow the clutch to be thrown in and the switch opened and brushes raised from the 70 commutator by withdrawing his foot from the pedal. However, I prefer that the actual starting of the engine by the throwing in of the clutch be controlled automatically when the motor armature reaches a certain 75 speed. In the present case, when the foot pedal is depressed, it is held in its lowermost position by means of a latch 43, which prevents the throwing in of the clutch 15 by the action of the spring 21, and prevents the 80 opening of the motor circuit, and the withdrawal of the brushes until after a predetermined speed is reached. While it is obvious that this latch may be withdrawn when the desired speed of the motor is reached by 85 a governor of the centrifugal type mechanically connected to the latch, I prefer to have the latch controlled by a so-called magnetic governor 44, which is shown in the drawings. This latch controlling governor includes a magnet coil 45 which is designed to be connected in circuit with the motor when the switch 29 is closed, and an armature 46 connected to the latch 43. During 90 the starting of the motor and until the predetermined speed limit is reached, the current passing through this coil causes a sufficiently strong magnetic field to attract the armature 46 against the tension of the spring 47, but as the motor speeds up, its counter-electromotive force increases gradually, decreasing the current passing through the motor and the coil 45. The strength of the magnetic field is thus gradually weakened, and when a predetermined speed is reached, 95 the spring 47 overcomes the pull of the magnet and withdraws the latch. The clutch 15 is then automatically thrown in by the action of the spring 21, which also causes the brushes to be shifted, the switch to be 100 opened, and restores the foot pedal to normal position.

I have thus provided a method and means for effectively starting the engine by a motor whose axis of rotation is coincident with 115 that of the crank shaft, and without requiring a motor of heavy starting torque and without drawing from the battery a heavy starting current.

Having thus described my invention, what I claim is:—

1. In combination with an internal combustion engine having a crank shaft, a starting motor having a stationary element and a rotary element mounted for rotation about the axis of the crank shaft, a switch for connecting the motor to a source of current, a clutch for connecting the rotary element of the motor to the crank shaft, and means for simultaneously throwing out the clutch to 120

disconnect the motor from the crank shaft and for closing the switch and a single operating device for said means.

2. In combination with an internal combustion engine having a crank shaft, a motor for starting the engine comprising a stationary element and a rotary element mounted for rotation about the axis of the crank shaft, a clutch for connecting and disconnecting the rotary element of the motor and the crank shaft, a switch for connecting the motor to a source of current, and brushes movable into contact with or away from the commutator of the motor, and a unitary mechanism for throwing out the clutch, for closing the switch and for shifting the brushes into engagement with the commutator.

3. In combination with an internal combustion engine, an electric motor including commutator brushes and a rotary member having a commutator, means for connecting and disconnecting the rotary member of the motor and the engine and means associated with said connecting and disconnecting means for shifting the brushes into and out of engagement with the commutator.

4. In combination with an internal combustion engine, an electric motor for starting the engine and including commutator brushes and a rotary member having a commutator, means including a clutch for connecting and disconnecting the motor and the engine, and means associated with said connecting and disconnecting means for lowering the brushes onto the commutator when the motor and engine are disconnected, and for raising the brushes from the commutator when the motor and engine are connected.

5. In combination with an internal combustion engine having a crank shaft, a starting motor, a source of current to which the motor is adapted to be electrically connected, and mechanism for connecting or disconnecting the motor and crank shaft, and si-

multaneously disconnecting or connecting the motor and source of current.

6. In combination with an internal combustion engine having a crank shaft, a starting motor, a source of current to which the motor is adapted to be electrically connected, a mechanical operative clutch for connecting and disconnecting the motor and crank shaft, means for connecting and disconnecting the motor and source of current and a single instrumentality for moving the clutch to disconnected position and simultaneously moving the said means to connect the motor and source of current or vice versa.

7. In combination with an internal combustion engine having a crank shaft, a motor for starting the engine and comprising a rotary member adapted when rotating to be connected to the crank shaft, a source of current to which the motor is adapted to be electrically connected, and means for connecting the rotary element and crank shaft, and disconnecting the motor and the source of current, or for disconnecting the rotary element and crank shaft, and connecting the motor and source of current.

8. In combination with an internal combustion engine having a crank shaft, an electric motor including a rotary element adapted to be started without load and to be connected when in motion to the crank shaft, a clutch for connecting and disconnecting the rotary element of the motor and crank shaft, a source of current, switching means for connecting and disconnecting the motor and source of current, and interconnected means for causing the opening of the switch and closing of the clutch, and the closing of the switch and opening of the clutch.

In testimony whereof, I hereunto affix my signature in the presence of two witnesses.

GEORGE R. WADSWORTH.
